UNITED STATES PATENT OFFICE.

SAMUEL DOBRIK AND LOUIS YACHNIS, OF NEW YORK, N. Y.

SOLE AND HEEL OF SHOES.

Application filed July 7, 1925. Serial No. 41,906.

The object of our invention is to provide an easily applied and detachable wear piece for the soles and heels of shoes so that when either becomes worn it will be possible to 5 replace the worn element or part without disturbing the parts which are still good and capable of further use. This object is accomplished by our invention, some embodiments of which are hereinafter more particularly set forth.

For a more detailed description of our invention, reference is to be had to the accompanying drawings, forming a part hereof, in which—

15 Figure 1 is a side elevation of a heel embodying our invention.

Figure 2 is a rear elevation of the same.

Figure 3 is an inverted plan view of the same.

20 Figure 4 is a longitudinal section of the same.

Figures 5 and 6 show the parts separated of which our improved heel is composed.

25 Figures 7 and 8 show metal reinforces used in the respective parts shown in Figures 5 and 6.

Figures 9 and 10 show our invention applied to the sole of a shoe with corresponding modifications.

30 Figure 11 is a side elevation, partially in section, of the structure disclosed in Figures 9 and 10.

Throughout the various views of the drawings, similar reference characters 35 designate similar parts.

A shoe 1, provided with our invention, has a heel 2 and a sole 3, the heel and sole being of the conventional kind and characteristics, except for differences hereinafter 40 specified, it being assumed that these parts are made of rubber, leather or other suitable material, in the conventional manner.

The heel 2 is given the usual shape and at 45 its rear it is provided with a removable piece 4 which is thickest at the extreme rear where the wear is greatest and tapers from this to its front edge 5. Its top edge 6 is preferably provided with lugs 7 which prevent all twisting of the piece 4 when in place. If 50 desired, these lugs may be omitted and the line 6 extended, as shown in dotted lines at 8 in Figures 1, 2 and 4.

The main part of the heel 2, which may be 55 designated generically by the character 9, is provided with a metal plate 10 which conforms to the outline of the upper surface 6

of the part 4 and the part 6 has a metal plate 11 which also conforms thereto and, in the preferred embodiment of our invention, the lugs 7 on the part 4 run to a U-shaped projection 12 which is covered by the plate 11 and the plate 10 has a corresponding depression 13 to receive the same. The metal plates 10 and 11 are preferably vulcanized in place and so firmly secured. To facilitate this, a surface of the plate 10 is roughened, as indicated at 14.

In the other embodiment of our invention, which is shown applied to the sole of a shoe, the sole 3 has a recessed part 15 at its front 70 end which is adapted to receive a corresponding part 16 which may be fitted thereto. The main part of the sole, which may be designated by the character 17, carries a metal plate 18 with three holes 19 which are 75 preferably screw threaded, although they may be made in any suitable way, and this plate with these holes is vulcanized in place. The other part 16 carries a metal plate 20 which is recessed so as to fit snug against 80 the plate 18 and engage the same and is vulcanized to the part 16. It has holes 21 through which screws 22 may pass to hold the part 16 in place. The part 16 has a projection 23 which enters a corresponding recess 24 in the part 17 and the part 17 is thinnest at its extreme front so that the part 16 may be fixed at its place where the wear 85 is greatest.

It will be understood that the part 6 is 90 held in place by screws 22 corresponding to the screws 22 used in holding the part 16 in place, although these screws are not shown, except in dotted lines in Figure 1.

In view of the foregoing, the use of our 95 improvement will be readily understood. It is used in the conventional manner and when the replaceable parts become worn, the screws 22 are removed, the worn parts removed and replaced and then the screws 22 100 are returned and thereby hold the removable parts in place the same as before. The advantage of this is that as the heels and soles become worn they may be restored to use in a condition substantially as good as 105 new by removing and replacing only a small part instead of the entire heel and this may be done without the aid of a cobbler or a cobbler's tools.

While we have shown and described some 110 embodiments of our invention, it is obvious that it is not restricted thereto, but that it

is broad enough to cover all structures that come within the scope of the annexed claim.

Having thus described our invention, what we claim is:

- 5 A bottom of a shoe having a removable piece with a top tapered from the end towards the middle, lugs to hold the parts in fixed relation projecting from said top and metal reinforces secured to said shoe-

bottom and removable piece, one metal reinforce inter-engaging with the other with intaglio-rilevato relation, said metal reinforces being on opposite surfaces.

In testimony whereof we have hereunto set our hands this 2d day of July, 1925.

SAMUEL DOBRIK.
LOUIS YACHNIS.
